John Licinit, Essington, and Anthony D'Alessandro,
Philadelphia, Pa., assignors to Jordon Refrigerator
Company, Philadelphia, Pa., a corporation of Pennsylvania

Application January 26, 1955, Serial No. 34,235

Term of patent 14 years

(Cl. D67—3)

FIG. 1

FIG. 2

Des. 175,264

FIG. 4

Fig. 1 is a front view of a combined refrigerator and freezer embodying our new design in closed position.

Fig. 2 is a side view thereof. The other side is the same.

Fig. 3 is a front elevational view thereof with the left door in open position.

Fig. 4 is a similar view with both doors in open position.

We claim:

The ornamental design for a combined refrigerator and freezer, as shown and described.
